CLAIM

The ornamental design for a spraying head for bottle with cleaning agent therein, as shown and described.

DESCRIPTION

FIG. 1 is a perspective view of a spraying head for bottle with cleaning agent therein;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a perspective view showing one application of the present invention, wherein the shading lines form no part of the claimed design.
